(57) **CLAIM**

The ornamental design for an automotive wheel, as shown and described.

DESCRIPTION

FIG. 1 is a perspective view of an automotive wheel front face showing my new design; and,

FIG. 2 is a front elevation view thereof.

In the drawings, the broken lines showing portions of the automotive wheel are provided for the purposes of illustrating environmental structure and form no part of the claimed design.

1 Claim, 2 Drawing Sheets

FIG. 1

FIG.2
